US00D936358S

(12) **United States Design Patent** (10) Patent No.: **US D936,358 S**
Lu (45) Date of Patent: **** Nov. 23, 2021**

(54) **EARPHONE CASE**(71) Applicant: **Shenzhen Quanmeng Technology Co., Ltd.**, Shenzhen (CN)(72) Inventor: **Xiying Lu**, Yiyang (CN)(73) Assignee: **SHENZHEN QUANMENG TECHNOLOGY CO., LTD.**, Shenzhen (CN)(***) Term: **15 Years**(21) Appl. No.: **29/719,714**(22) Filed: **Jan. 7, 2020**(51) LOC (13) Cl. **03-01**

Primary Examiner — April Rivas*Assistant Examiner* — Caitlin A Laverty(57) **CLAIM**

The ornamental design for an earphone case, as shown and described.

DESCRIPTION

FIG. 1 is a main view of the earphone case;

FIG. 2 is a rear view thereof;

FIG. 3 is a left view thereof;

FIG. 4 is a right view thereof;

FIG. 5 is a top view thereof;

FIG. 6 is a bottom view thereof; and,

(Continued)

FIG. 7 is a perspective view thereof.
The broken lines show portions of the earphone case and
form no part of the claimed design.

1 Claim, 4 Drawing Sheets
